UNITED STATES PATENT OFFICE.

JOHN H. BICKLEY, OF DOVER, NEW JERSEY.

FENCE.

SPECIFICATION forming part of Letters Patent No. 319,057, dated June 2, 1885.

Application filed September 8, 1884. (No model.)

To all whom it may concern:

Be it known that I, JOHN H. BICKLEY, a citizen of the United States, residing in Dover, Morris county, New Jersey, have invented certain new and useful Improvements in Fences, 5 fully described and represented in the following specification and the accompanying drawings, forming a part of the same.

This invention consists in a combination, with 10 angle-iron rails having integral hooks formed thereon and pointed toward the edge of the rail, of flexible wire bent back and forth between the rails, over said hooks, and secured thereto, as by clinching the hooks down upon 15 the wire.

In the drawings a panel of fence is shown with two posts, A A, and two rails with wire woven thereon in two differentmet hods; also a detached panel.

20 Figure 1 shows a front view of such fence; Fig. 2, a side view of the post with sections of the rails, and Fig. 3 a perspective view of a piece of the rail detached. Fig. 4 is a view of a panel detached.

25 The rail is formed of horizontal and vertical flanges, lettered, respectively, B and B'; and the hooks *c* are formed by punching tongues from the flange B', leaving openings *d* in the flange by the side of the hooks, the latter being punched and bent in each case so that the 30 rails when secured parallel to one another, as at the top and bottom of the posts, may afford two parallel series of hooks, over which a continuous wire or wires may be bent back and 35 forth from one rail to the other, so as to produce a net-work, depending in fineness upon the distances of the separate hooks and the disposition of the wire upon them.

Two methods of applying wire to the hooks 40 are shown in Fig. 1, in both of which wires *e* *e'* are shown, one of which is applied so as to avoid alternate hooks upon the opposite rails, to which hooks the second wire, *e'*, is applied. Twice as many wires may be used, the same being inclined much more than in Fig. 1, to produce a finer netting, each wire being applied 45 to every fourth hook upon the opposite rails. The angle form of the rails enables me to secure stiffness in both directions, in combination with the thinness of metal required to pro-

duce the hooks in the manner described, while the bending of the hooks transversely to the length of the rail affords a support for the wire when woven back and forth in the manner described. The ends of the wire may be looped 55 around the hook, as at *f* in Fig. 1; or the hook may be hammered down to the rail to pinch the wire.

I am aware that it is not new to secure a wire to a metallic fence-rail by pinching the same 60 within the hook, and I do not therefore claim such construction, except in the combinations herein shown and described, in which the hooks are bent transversely to the length of the rail, so that the hooks may operate effectively to 65 support the wire, whether the hooks are bent down upon the wire or not. By this construction I secure lightness and stiffness in the rails employed, and a construction by which an operator can apply the wire successfully to a great 70 length of fence without bending such hook to secure the wire, as in constructions where the wire projects above and below the rails like pickets. My construction is also adapted for the manufacture and sale of the fence in sections or panels sixteen feet in length, for which 75 purpose I apply the wires to the rails by suitable machinery, clinching all the hooks as the wire is bent over them, and cutting the wires off at the ends of the fence-panel just beyond 80 the last hook at each end of the rail, and bending the same over the back of the hook, as at *f* in Fig. 1.

Besides the clinching of the hooks, the panels may be supported by cross-bars of wood or 85 metal. Such a panel is shown in Fig. 4, including cross-bars *g*, secured between the rails at intervals by nails to hold the same apart until placed upon the posts. Such panels may be coated with asphaltum varnish or with 90 melted zinc by the ordinary galvanizing process, the latter coating serving not only to protect the material of the fence from rust, but to solder all the joints together, and to greatly increase the rigidity of the structure. The rails 95 are provided with nail-holes *i* about eight feet apart, and in applying such rails to the posts the operator makes a saw-kerf, *h*, at the desired level in the post to fit the flange B, and after placing the flange therein secures the 100

flange B' to the face of the post by nails *j*, as shown in Fig. 1, the ends of the rails being preferably overlapped, as shown at the bottom rail in Fig. 1, although the ends may be butted, 5 as shown at the upper rail in the same figure.

I am aware that it is not new to use angle-iron for fence-rails, and that tongues have been formed upon metallic fence-bars to clasp vertical rods or pickets by friction to the rail. I 10 do not therefore claim either the use of the angle-iron rail or of tongues, broadly, but the combination of the two in the construction herein described, whereby the tongues are projected, respectively, toward the top and 15 bottom of the fence, as clearly shown in Fig. 2, so as to retain the flexible wires when bent over the same and drawn toward the opposite rail in the manner described.

Having thus set forth the nature of my invention, I claim as follows:

1. The combination, with two angle-rails, B'

B', arranged parallel to one another and provided with the integral hooks *c*, projected away from the opposite rail in the manner described, of the wire or wires woven back and forth over 25 the hooks, substantially as herein shown and described.

2. As a new article of manufacture, the fence-panel composed of the parallel metallic angle-panels formed with integral hooks projected 30 away from the opposite rail, and having wire woven transversely between the rails and secured to the hooks by bending the latter, substantially as herein shown and described.

In testimony whereof I have hereunto set my 35 hand in the presence of two subscribing witnesses.

JOHN H. BICKLEY.

Witnesses:

HENRY F. GÖKEN,
L. LEE.
